[57] CLAIM

The design for the litter removal tool or the like, as shown and described.

DESCRIPTION

FIG. 1 is an isometric view of a litter removal tool or the like showing my new design;

FIG. 2 is a top plan view thereof, the bottom being a mirror image of the top shown;

FIG. 3 is a side elevational view thereof;

FIG. 4 is a elevational view taken from the side opposite that shown in FIG. 3;

FIG. 5 is a rear elevational view thereof;

FIG. 6 is a front elevational view thereof;

FIG. 7 is an isometric view of a second embodiment of the litter removal tool or the like shown in FIG. 1; and FIG. 8 is an isometric view of a third embodiment of the litter removal tool or the like shown in FIG. 1.

FIG- 7

FIG- 8
